(No Model.)

E. J. HALL.

FOUNTAIN PEN.

No. 341,001.

Patented May 4, 1886.

ATTEST,

John H. Redstone
L. E. Redstone

INVENTOR

Edwin J. Hall

UNITED STATES PATENT OFFICE.

EDWIN J. HALL, OF SAN FRANCISCO, CALIFORNIA.

FOUNTAIN-PEN.

SPECIFICATION forming part of Letters Patent No. 341,001, dated May 4, 1886.

Application filed October 16, 1885. Serial No. 180,062. (No model.)

To all whom it may concern:

Be it known that I, EDWIN J. HALL, a citizen of the United States, residing in the city and county of San Francisco, and State of California, have invented a new and useful Fountain Pen-Holder, of which the following is a specification.

My invention relates to improvements in fountain pen-holders; and it consists in a certain construction and arrangement, which will be more readily understood by reference to the accompanying drawings and the letters marked thereon.

Figure 1 is a side elevation; Fig. 2, a longitudinal section showing the valves closed; Fig. 3, a longitudinal section showing the valves opened; Fig. 4, a longitudinal section showing the pen-case with the cap and upper valve-seat removed; Fig. 5, a transverse sectional view of the combined cap and valve thumb-piece; Fig. 6, a transverse section of the combined stem-guide and valve-seat; and Fig. 7 is a horizontal section showing the pen-holder cut through the dotted lines *a a* in Fig. 4.

The following is the construction of the same:

A represents the outer case, B the combined cap and valve thumb-piece, and C the female screw by which the same is attached to the valve-stem.

D shows the combined stem-guide and valve-seat for the upper valve; E, the guide-hole for the valve-stem; F, the valve-seat.

35 G represents the guide-arms of the valve-stem and the upper valve.

H represents the valve-stem; J, the valve-spring.

K represents the valve-seat for the lower valve.

40 L represents the lower valve.

M represents the pen-point.

N represents the collar which forms the seat for the valve-spring.

45 P represents the pen-case.

S represents a rubber washer on the valve G to serve as a packing.

G' and G'' represent the guide-arms attached to the valve G.

I form the outer case and cap of gold, silver, or any suitable metal for a neat pen-holder, and the spring and valves of such metals as are usually employed in similar construction.

I employ any ordinary gold or steel pen, such as is employed in other pen-holders.

To fill the pen, I unscrew the cap and thumb-piece B and take out the upper valve-seat and stem-guide. This opening is then sufficiently large to allow the ink to be poured in at the top and fill the case.

The following is the operation of the same: When the fountain pen-holder is filled and the combined valve-stem guide and valve-seat D is screwed in, and the cap and thumb-piece B screwed on, the thumb is gently pressed upon the cap B, and the spring J, yielding, opens both the upper valve, G, and lower valve, L, allowing a drop of ink to flow out into the pen M. The guide-arms of the valve G are designed to prevent the turning of the valve-stem when the cap B and upper valve, D, are being unscrewed or screwed on. As the valve-stem H is pressed down, opening the valves G and L, the upper valve, G, admits the air at the top end of the pen-holder A, and allows the ink to flow out at the lower valve, L, and fill the pen, as required.

Having thus described my invention, what I claim, and desire to secure by Letters Patent, is—

In a fountain pen, the case A, having the stem-guide and valve-seat D F located in its upper end, and valve-seat K in the lower end thereof, in combination with valve-stem H, having the valve G, provided with guide-arms G' and valve L at its upper and lower ends, respectively, the cap and thumb-piece B, screwed to the top of the stem H, and valve-spring J, all constructed and operating substantially as set forth.

EDWIN J. HALL.
